(57) **CLAIM**

The ornamental design for a flashlight with clip interface, as shown and described.

DESCRIPTION

FIG. 1 is a perspective view showing my new design for a flashlight with clip interface;

FIG. 2 is a bottom view thereof;

FIG. 3 is a top view thereof;

FIG. 4 is a right side view thereof;

FIG. 5 is a left side view thereof;

FIG. 6 is a back view thereof;

FIG. 7 is a front view thereof; and,

FIG. 8 is a perspective view showing the clip interface in an alternate position.

The broken lines depicted in the figures are for reference only and do not comprise part of the claimed subject matter.
